UNITED STATES PATENT OFFICE.

JAMES W. MONTGOMERY, OF THOMASVILLE, GEORGIA, ASSIGNOR TO W. J. BURNETT,
OF THOMASVILLE, GEORGIA.

PLOW.

Application filed May 29, 1922. Serial No. 564,391.

To all whom it may concern:

Be it known that I, JAMES W. MONTGOMERY, a citizen of the United States, residing at Thomasville, in the county of Thomas and State of Georgia, have invented a new and useful Plow, of which the following is a specification.

This invention relates to a plow and it is designed more particularly as an improvement upon the structure disclosed in Patent No. 1,147,420 issued to me on July 20, 1915.

It is an object of the present invention to provide the plow with a runner so constructed that it will not unduly limit the adjustment of the king bolt used for attaching the plow point to the standard. It is the practice among farmers to gradually adjust their plows along the stocks or standards as the points wear off but in those plows utilizing runners the adjustment is limited and it becomes necessary to discard the point before the maximum wear has been obtained. In the present invention, however, the runner is so mounted that the bolt which connects the point to the standard or stock can be adjusted downwardly practically to the lower extremity of the stock or standard.

Another object is to provide a runner to which either single or double sweeps or scrapers can be attached and which will hold them at any desired angles to the runner.

With the foregoing and other objects in view which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings the preferred form of the invention has been shown.

In said drawings,

Figure 1 is a vertical section through the plow point and the stock and showing adjacent parts.

Figure 2 is a plan view of the runner and showing a pair of single scrapers attached thereto.

Figure 3 is a view partly in side elevation and partly in section showing the means employed for attaching a double scraper to the runner.

Figure 4 is an enlarged section on line 4-4, Figure 3.

Referring to the figures by characters of reference 1 designates a metal beam to the downwardly curved rear end portion of which are bolted the side portions of a metal stock or standard 2, there being a longitudinal slot 3 formed within this stock or standard between the lower end of the beam 1 and the lower end of the stock, as shown particularly in Figure 1. This slot is designed to receive the king bolt 4 used for fastening the plow point 5 to the stock. This plow point is preferably formed with a shank 6 having a longitudinal slot 7 through which the bolt 4 extends, there being a nut 8 on the rear end of the bolt and engaging the stock whereby the head of the bolt can be caused to bind the shank of the plow against the stock. The plow point can be of any form desired and can, if preferred, be provided with a mold board integral with or separate from the point.

A runner 26 is provided back of the stock or standard 2 and the front end of this runner is forked as shown at 27 so as to straddle the lower end of the stock 2, there being a bolt 28 for pivotally attaching this forked end of the runner to the stock. The fork 27 is so proportioned that if desired the bolt 4 and its nut 8 can be adjusted downwardly into the fork in order to hold the plow point at its lowermost position. This will be obvious by referring to Figure 1.

The runner 26 is provided, back of the fork with an upstanding portion 29 having flat parallel side faces and a front face which is concaved from end to end and inclined downwardly and forwardly, this front face being toothed as shown at 30. An opening 31 is extended transversely through the runner at a point near the fork and a slot 32, which is concentric with this opening, extends transversely through the upwardly projecting portion 29.

A toothed block or saddle 38 is placed astride the concaved toothed face 30 of the runner so that the teeth in this saddle can engage the teeth 30. The sides of the saddle are designed to lap the openings 31 and 32 in the runner. A longitudinal slot 39 is formed in the front of the block and a groove 40 is provided in the toothed face of the block to receive the head 41 of a bolt 42 adjustable in the slot 39. This bolt ex-

tends through the intermediate portion 43 of the scraper and from which portion extend the rearwardly diverging wings 44. Obviously with this arrangement the scraper 5 can be adjusted vertically or upwardly along the block or saddle 38 so as to bring the scraper to a desired elevation.

The plow herein described is susceptible of a large number of adjustments and is designed to be used for a great variety of purposes. Importance is attached to the use of the open fork 27 whereby the king bolt 4 can be adjusted to the lower limit of the slot 3, thereby allowing the point to be used 15 when worn down to the smallest possible size. The runner 26 can be provided with upwardly extending ears 25 for pivotal engagement by a bar 23 whereby said runner can be adjusted angularly by means of any 20 suitable mechanism provided for that purpose.

Bolts 35 and 36 serve to hold the saddle 38 in position as shown.

What is claimed is:—

In a plow the combination with a stock, 25 of an angularly adjustable runner having a forked end straddling and pivotally connected to the stock, an upwardly projecting portion on the runner between the ends thereof, there being a series of transverse 30 teeth upon the front face of the upwardly projecting portion, said series extending downwardly into the forked portion of the runner, a toothed member adjustably mounted on the toothed face of said upwardly 35 projected portion, and a sweep secured to and extending across the front of the toothed member and back of the stock.

In testimony that I claim the foregoing as my own, I have hereto affixed my signature.

JAMES W. MONTGOMERY.
